[57] CLAIM

The ornamental design for a vehicle beverage holder, as shown and described.

DESCRIPTION

FIG. 1 is a front elevational view of the vehicle beverage holder of the present invention;

FIG. 2 is a back elevational view of the vehicle beverage holder of FIG. 1;

FIG. 3 is a top plan elevational view of the vehicle beverage holder of FIG. 1;

FIG. 4 is a bottom plan view of the vehicle beverage holder of FIG. 1;

FIG. 5 is a right side elevational view of the vehicle beverage holder of FIG. 1; and,

FIG. 6 is an assembled front, right, top perspective view of the vehicle beverage holder of FIG. 1.

The left side view of the vehicle beverage holder is a mirror image of FIG. 5.
